Attorney

UNITED STATES PATENT OFFICE.

HERBERT W. OWEN, OF LEWISTON, MAINE, ASSIGNOR TO DRAPER CORPORATION, OF HOPEDALE, MASSACHUSETTS, A CORPORATION OF MAINE.

SHUTTLE TENSION.

1,283,882.

Specification of Letters Patent.

Patented Nov. 5, 1918.

Application filed June 30, 1917. Serial No. 177,937.

To all whom it may concern:

Be it known that I, HERBERT W. OWEN, a citizen of the United States, residing at Lewiston, county of Androscoggin, and 5 State of Maine, have invented an Improvement in Shuttle Tensions, of which the following description, in connection with the accompanying drawings, is a specification, like characters on the drawings representing 10 like parts.

The invention to be hereinafter described relates to loom shuttles, and more particularly to tension devices employed in such shuttles to act upon the filling or weft.

15 During the weaving operation, the filling is rapidly drawn from the filling carrier as the shuttle is picked from one shuttle-box to the other and is liable to overrun, particularly when the shuttle is suddenly arrested in the shuttle-box. In consequence of this, the filling may become snarled or kinked which at times may cause breakage, or in case of self-threading shuttles employed in filling replenishing looms, such 20 condition of the filling may cause the shuttle to become unthreaded. These undesirable conditions are emphasized where the filling is coarse or heavy, and whenever they occur they may either cause loom stoppage or an 25 unnecessary operation of the replenishing mechanism with resulting waste and cost of production.

An important feature of the present invention therefore, consists of a tension device bearing directly upon the mass of filling in the shuttle and extending longitudinally of the filling mass at the side thereof in non-intersecting relation with the axis of the filling carrier. This characteristic of the invention, while rendering the tension device effective in preventing over-running of the filling in any type of shuttle, renders it particularly advantageous in a shuttle where the filling is to be replenished 40 from time to time by the automatic insertion and ejection of filling carriers, because while acting upon the body of the filling in the shuttle, it does not interfere with the automatic ejection of a filling carrier.

45 Shuttles which are to be automatically replenished with filling usually have an enlarged base to engage the holding means in the shuttle. It is, therefore, important that the longitudinally-extending tension device 50 shall not impede the passage of the enlarged

base through the opening in the wall of the shuttle when the filling is replenished and the old filling carrier is ejected. Another feature of the invention, therefore, consists of a tension device having two legs which 60 diverge from a point near the tip of the filling carrier toward the base and each of which bear upon the mass of filling at one side of the axis of the carrier, so that the carrier may be readily ejected. 65

Other objects and features of the invention in addition to those stated, will be hereinafter described in connection with the accompanying drawing which shows certain forms of the invention well adapted to carry 70 it into practical effect, and then the various features of the invention will be set forth in the claims.

In the drawings:--

Figure 1 is a plan view of a shuttle provided with a tension device embodying the present invention; 75

Fig. 2 is a bottom plan view of the shuttle shown by Fig. 1;

Fig. 3 is a partial longitudinal section of 80 the shuttle shown by Fig. 1, parts being omitted, and including a fragmentary sectional portion illustrating the manner of securing one end of the tension device to the shuttle-body;

Fig. 4 is a plan view of a shuttle containing a modified form of the invention, the filling carrier being omitted, and some of the parts being broken away; 85

Fig. 5 is a perspective view looking at the 90 bottom portion of a shuttle containing a modified form of the invention; and

Fig. 6 is a detached detail showing the tension regulating device employed in the modified construction shown by Fig. 5. 95

Referring more particularly to Figs. 1, 2 and 3: The shuttle 1 is illustrated as of the filling replenishing type, having an opening 2 in its top and an opening 3 in its bottom for the purpose of inserting and ejecting 100 a filling carrier in a manner well understood by those skilled in the art. The shuttle body has secured thereto the guide 4 for directing the filling carrier into proper holding relation with the holding means for 105 the filling carrier, which, in the present instance of the invention, comprises the jaws 5, 5.

Shuttles of the character illustrated are usually provided with a self-threading de- 110

2
vice which automatically effects the threading of the filling into the shuttle eye when the shuttle is picked after a replenishing operation. In the present instance, the 5 threading device consists of a block 6 of usual construction, and having a projecting stud 7 which enters a recess 8 in the shuttle body to assist in holding the threading block in operative position. A transversely-extending bolt 9 passes through the lower portion 10 of the threading block and into the shuttle body, the construction being such that the threading block may be properly maintained in its operative relation with the 15 shuttle body.

The filling carrier 10 may be of any appropriate character, and as illustrated in the present instance of the invention, comprises a bobbin having an enlarged base portion 11 20 provided with the jaw-engaging rings 12 to be received by the usual grooves in the bobbin-holding jaws 5. The construction so far described may be of any approved character, such that when the shuttle is to be replenished by a change of filling carriers, the old filling carrier may be forced through the bottom opening 3 of the shuttle as the new filling carrier is inserted into the shuttle.

In order that the filling shall not balloon 30 or become snarled, or kinked, during the weaving operation, it is desirable that a too free delivery of the filling from the filling carrier may be prevented, especially when the shuttle comes to rest in the shuttle-box 35 after its flight across the lay. To this end the present invention contemplates a tension device extending longitudinally of the shuttle, which shall engage the body of the filling at one side of the longitudinal axis of the 40 filling carrier and not interfere with the ejection of the filling carrier when replenishment of filling is to be effected.

In the form of the invention illustrated by Fig. 1, the tension device consists of a flexible member 13 having the leg portions 14, 45 one arranged at either side of the longitudinal axis of the filling carrier, the construction being such that when the filling carrier is to be ejected from the shuttle it may readily pass between the legs 14 of the flexible member 13. In the illustrated form of the invention, the legs 14 of the tension device may be formed by splitting or bifurcating the flexible member 13, one end of the flexible member 13 being secured to the shuttle body adjacent the tip end of the filling carrier and the ends of the leg portions 14 being secured adjacent the base portion of the filling carrier, said leg portions 14 diverging 55 60 from a point adjacent the tip of the bobbin toward the base of the filling carrier, substantially as illustrated in Figs. 1 and 2. The flexible member 13 may be secured to the shuttle body by any appropriate means, but 65 as shown in the illustrated form of the in-

vention, the stud or pin 7 of the threading block is passed through the end portion 15 of the flexible member 13, and the ends of the legs 14 are secured to the shuttle body adjacent the base portion of the bobbin or filling 70 carrier. This may be effected in various ways, and as illustrated, the shuttle body is provided with an opening 16, one at either side of the shuttle body adjacent the base of the bobbin, and the ends of the legs 14 respectively, are inserted in such openings where they may be secured by a plug of wood or similar material, 17.

From the construction described, it will be apparent that the legs of the tension device 80 are more widely separated adjacent the base portion of the bobbin or filling carrier to permit ejection of the filling carrier or bobbin when the shuttle is to be replenished with filling, and that said legs converge until they 85 meet adjacent or slightly beyond the tip portion of the bobbin at 18, the construction being such that as the filling carrier or bobbin is pushed downwardly to be ejected from the shuttle, the base portion thereof will readily 90 pass between the widely separated legs 14, and the tip portion 19 of the filling carrier or bobbin will pass downwardly between the more contracted opening between the legs 14, the flexible or yielding character of the ten- 95 sion device yielding sufficiently at such time to permit the tip end 19 of the filling carrier or bobbin to pass between the legs of the tension device.

Since the filling is wound upon the filling carrier or bobbin by what is technically known as the filling wind, it is drawn from the filling carrier or bobbin in conical layers from the end thereof. It is therefore desirable that the legs 14 of the tension device 100 converge toward the tip end of the bobbin or filling carrier and in order to secure a more effective contact between the legs of the tension device and the cone portion of the filling carrier near the tip thereof, it may be desirable, in some instances, to secure the tension device to the shuttle body adjacent the tip portion of the bobbin or filling carrier at a point nearer the longitudinal axis of the filling carrier than the ends of the legs 14 110 are secured to the shuttle body. This is effected in the present instance of the invention by carrying the end 15 of the tension device above the wall 20 of the shuttle body, as indicated in Fig. 3, the construction being 115 such that the legs 14 of the tension device in addition to converging toward the tip end of the bobbin, will gradually approach nearer to the longitudinal axis of the filling carrier or bobbin as they approach the tip portion 12 thereof.

The tension device 13 is preferably formed of a flexible or yielding material that will not injure the filling, such, for instance, as leather or raw hide, or other suit- 125

able substance; but in addition to the yielding character inherent in the tension device itself, it may be desirable at times to provide a further yielding characteristic to the 5 tension device. This is effected in the modification illustrated in Fig. 4 by securing the legs 14 to the shuttle body by means of the springs 21. One end of a spring 21 may be secured to one end of a leg 14, and the 10 other end to the shuttle body by suitable means such as a pin 22, the particulars in this respect being susceptible of variation.

In the modification of the invention as 15 illustrated by Fig. 5, means are provided for adjusting the action of the tension device to suit the conditions of use. This may be variously effected, but in the instance illustrated in Fig. 5, the legs 14 of the tension device are secured to a rotatable pin 23 20 passed transversely through the body of the shuttle as indicated in Fig. 5. The pin 23 may be provided with a slotted head 24, by which it may be rotated to adjust the effective action of the legs 14 upon the mass or 25 body of filling in the shuttle; and when it has been rotated to the desired extent, it may be secured in such adjusted position by suitable means such, for instance, as the set screw 25.

30 The ends of the legs 14 may be secured to the adjusting device 23 in various ways, but as illustrated in Fig. 6, the rotatable pin 23 is provided with openings 26 in which the 35 ends of the legs 14 of the tension device are inserted and secured.

What is claimed is:—

1. A loom shuttle having means for detachably holding a filling carrier and provided with an opening in its walls for the 40 passage of the filling carrier therethrough, and a tension device having two leg portions extending longitudinally of the shuttle, one at each side of the axis of the filling carrier to bear upon the filling and permit ejection 45 of the filling carrier from the shuttle by passing between the legs of the tension device.

2. A loom shuttle adapted to hold a filling carrier and permit it to be bodily ejected 50 therefrom, and a tension device having longitudinally-extending members to bear upon the filling at each side of the axis of the filling carrier and converging from one end 55 of the filling carrier toward the other that the filling carrier may pass between the two members as it is ejected from the shuttle.

3. A loom shuttle provided with jaws for detachably holding a filling carrier and having an opening through opposite walls for the introduction and ejection of the carrier, a tension device having a leg portion extending longitudinally of the shuttle at one side of the axis of the filling carrier to bear 60 upon the body of the filling on the carrier, and means for securing the ends of the ten-

sion device to the shuttle body that the carrier may readily pass when ejected from the shuttle.

4. A loom shuttle in which the filling is adapted to be automatically replenished by 70 the insertion and ejection of a filling carrier, provided with a tension device having one end secured to the shuttle body near the base and at one side of the axis of the filling carrier in the shuttle and the other end secured to the shuttle body near the tip end and nearer the axis of the filling carrier that the tension device may bear upon the mass of filling and yet permit the filling carrier to be readily ejected bodily from the shuttle. 75

5. A loom shuttle in which the filling is adapted to be automatically replenished by 80 the insertion and ejection of a filling carrier, provided with a tension device having one end secured near the base of the filling carrier in the shuttle and the other end secured to the shuttle body near the tip and nearer the axis of the filling carrier that the tension device may bear upon the mass of filling 85 in the shuttle and permit the filling carrier to be readily ejected, and yielding means 90 acting to hold the tension device against the mass of filling.

6. A loom shuttle in which the filling is adapted to be automatically replenished by 95 the insertion and ejection of a filling carrier, provided with a yielding tension device having leg portions diverging from a point near the tip of the filling carrier in the shuttle toward the base of the filling 100 carrier, said leg portions adapted to bear upon the mass of filling at each side of the longitudinal axis of the filling carrier and permitting the filling carrier to pass between the leg portions when it is ejected. 105

7. A loom shuttle having means for detachably holding a filling carrier and provided with an opening in its walls for the passage of the filling carrier therethrough, a tension device having two leg portions 110 extending longitudinally of the shuttle, one at each side of the axis of the filling carrier to bear upon the filling and permit ejection 115 of the filling carrier from the shuttle by passing between the legs of the tension device, and means for adjusting the action of the tension device.

8. In a loom shuttle, the combination of a shuttle body having an opening for the reception of a filling carrier, and a tension 120 device having leg portions extending diagonally from one end of the filling carrier receiving opening of the shuttle to the other, the distance between the legs of the tension device adjacent the base of the filling carrier in the shuttle being greater than the 125 distance between the legs of the tension device adjacent the tip end of the filling carrier.

9. In a loom shuttle, the combination of a 130

- shuttle body having an opening for the reception of a filling carrier, a tension device having leg portions extending diagonally from one end of the filling carrier receiving 5 opening of the shuttle to the other, the distance between the legs of the tension device adjacent the base of the filling carrier in the shuttle being greater than the distance between the legs of the tension device adjacent 10 the tip end of the filling carrier, and yielding means acting longitudinally of the tension device to hold the legs of the tension device against the mass of yarn in the shuttle.
15. In a loom shuttle, the combination with a shuttle body having a filling carrier receiving opening, of a tension device having leg portions formed of flexible material and extending longitudinally of the receiving 20 opening each to bear upon the mass of filling at one side of the axis of the filling carrier, that the filling carrier may pass between the leg portions, and means for securing the ends of the tension device at opposite end portions of the receiving opening.
25. 11. A tension device for loom shuttles, comprising, in combination, a strip of flexible material having diverging leg portions adapted to bear upon the filling in a shuttle 30 at opposite sides of the axis of the filling carrier, and means for securing one end portion of the tension device yieldingly to the body of the shuttle.
35. 12. A loom shuttle adapted to hold a filling carrier and permit it to be bodily ejected
- therefrom, and a tension device extending longitudinally of the shuttle to bear upon the mass of filling at one side of the longitudinal axis of the filling carrier or bobbin that the filling carrier or bobbin may pass 40 the tension device when the carrier or bobbin is bodily ejected from the shuttle.
13. In a loom shuttle, the combination with a shuttle body having a filling carrier receiving opening, and an ejecting opening, 45 of a tension device extending longitudinally of the shuttle to bear upon the mass of filling in the shuttle, and means for securing the tension device to the shuttle body with the end adjacent the tip of the filling carrier nearer the longitudinal axis of the filling carrier than the end adjacent the base of the filling carrier that the tension device may bear upon the filling at one side of the longitudinal axis of the carrier or bobbin 50 and permit the carrier or bobbin to pass when ejected from the shuttle.
14. A loom shuttle provided with an opening in its walls for the passage therethrough of a filling carrier or bobbin, and a tension device extending longitudinally of the shuttle to bear upon the filling at each side of the axis of the filling carrier or bobbin and permit the passage of the filling carrier, and means for securing opposite ends of the 55 tension device to the shuttle.

In testimony whereof, I have signed my name to this specification.

HERBERT W. OWEN.
